UNITED STATES PATENT OFFICE.

CHARLES E. BARRIE, OF BRATTLEBORO, VERMONT.

ROAD-SWEEPER.

1,335,637.

Specification of Letters Patent. Patented Mar. 30, 1920.

Application filed June 8, 1918. Serial No. 238,948.

To all whom it may concern:

Be it known that I, CHARLES E. BARRIE, a citizen of the United States, and a resident of Brattleboro, in the county of Windham 5 and State of Vermont, have invented a new and Improved Road-Sweeper, of which the following is a full, clear, and exact description.

This invention relates to sweepers and has 10 for an object the provision of an improved construction which may be used for sweeping roads, streets and the like under ordinary conditions, or may be used for sweeping snow or other matter in considerable 15 quantities.

A further object of the invention is to provide an improved construction wherein the elevating means extends to a point near the road so that the sweeping members or 20 collecting members may not raise the dirt, snow, or other matter.

A still further object of the invention is to provide a sweeping and elevating device for a vehicle which will operate to collect 25 the dirt or other matter being swept while the vehicle is moving at an appreciable speed, so that the streets may be cleaned without shutting off their general traffic.

In the accompanying drawings:

30 Figure 1 is a longitudinal vertical section through the rear part of the machine disclosing an embodiment of the invention.

Fig. 2 is a top plan view on line 2—2 of Fig. 1, the same being on a reduced scale.

35 Fig. 3 is a rear view of the structure shown in Fig. 1.

Fig. 4 is a fragmentary sectional view through Fig. 1 on line 4—4.

40 Fig. 5 is a detail fragmentary view showing a slightly modified form of collecting means wherein a scraper is used instead of a brush.

45 Referring to the accompanying drawing by numerals, 1 indicates the frame of an automobile or other vehicle, the detail features of which form no part of the present invention. It will, of course, be understood that a power driven vehicle may be used or a horse drawn vehicle without departing 50 from the spirit of the invention. When the device is mounted on a power driven vehicle power is transmitted from the engine through shaft 2 to the worm 3, which in turn transmits power to the worm gear 4 secured to the transverse shaft 5 mounted in suitable bearing boxes on the frame 1.

Supported by the shaft 5 are sprocket wheels 6 and 7 which accommodate chains 8 and 9, which chains in turn pass over sprocket wheels connected with the driving or traction wheels 10 and 11. The wheels 10 and 11 are rigidly secured to tubular stub shafts 12 and 13, which stub shafts are loosely mounted on a fixed non-rotatable bearing shaft 14. The stub shaft 13 is connected to 60 the auxiliary shaft 15 through gears 16 and 17 and a clutch 18, which clutch is operated by lever 19 and rod 20 extending to the front of the machine. The stub shaft 12 transmits power through the gears 21 and 70 22 and the clutch 23 to the auxiliary shaft 24. Clutch 23 is operated by a lever 25 which in turn is actuated by rod 26 extending to the front of the machine whereby when the rods 20 and 26 are actuated the 75 clutches will also be actuated for turning on and off the power to the auxiliary shafts 15 and 24. These shafts are supported by suitable bearing boxes carried by what may be termed the elevator 27, which elevator is 80 provided with a sheet metal base 28 extending from the rear of the machine as shown in Fig. 1 forwardly to the bend 29 and from thence upwardly to the horizontal section 30 of the chain 31. Suitable brackets 32 and 85 33 are mounted on the axle 14, said brackets being rigidly secured to the plate 28 in any desired manner whereby the plate is permitted a swinging movement around the axle 14 and thereby the elevator 27 may 90 move up and down in passing over inequalities in the roadbed or street.

To provide a proper bearing surface for the plate 28 a number of runners 34 are provided which are rigidly secured to the horizontal or bottom sections 35 of plate 28 as 95 shown particularly in Figs. 1 and 2. The auxiliary shaft 15 has a sprocket wheel 36 rigidly secured thereto, said sprocket wheel accommodating the chain 37, which chain 100 passes over a sprocket wheel 38 mounted on the shaft 39. Shaft 39 carries sprocket wheels 40 and 41, said sprocket wheels accommodating the chain 31 as shown particularly in Fig. 1. The chain 42 passes 105 over a sprocket 43 on auxiliary shaft 24 and also one of the sprockets 38 on the shaft 39. A sprocket 44 is rigidly secured to the auxiliary shaft 24 and accommodates chain 45, which chain passes over a sprocket 46 operating the shaft 47, which shaft rotates the beveled gear 48 meshing with the beveled 110

gear 49. Beveled gear 49 is connected to the brush 50 through a universal joint 51 whereby said brush is rotated, but is allowed to accommodate itself to the inequalities of the street or roadway. A sprocket 52 is connected to the auxiliary shaft 15 and accommodates a chain 53, which acts similar to chain 45, but rotates the sprocket 54 on the shaft 55, which carries the beveled gear 56. The gear 56 meshes with the beveled gear 57 which last mentioned gear rotates the brush 58, said beveled gear acting through the universal connection 59. By the construction just described when the automobile is moved along the power will be transmitted to the brushes 50 and 58 for rotating the same, and as these brushes are arranged on an angle the dirt or other matter being operated upon will be gradually worked toward the center and evenly deposited on the elevator 27. Brackets 60 are hinged at 62 and 63 on the frame 1 said brackets having suitable bearing boxes at the outer end for accommodating the supporting shaft of the brushes 50 and 58 as shown in Fig. 2. The inner ends of the brushes discharge the dirt on to the elevator 27 which elevator is provided with chains 31 to which flights or lifting members 64 are secured. These lifting members may be of any size and act to lift the dirt or other matter being operated upon upwardly at a slight angle as shown in Fig. 1 until the chains reach the horizontal position indicated by numeral 30 in Fig. 1, whereupon the dirt or other matter will drop on to the bottom 65, and as this bottom is at an incline the dirt or other matter will gravitate to the bottom 66 of the box or body 67. This box or body is pivotally supported at 68 and is provided with a door 69 at the rear end which is hinged at the top and fastened in any suitable manner at the bottom. The bottom 65 is provided with a V-shaped member 70 whereby as the dirt is discharged on the bottom 65 it will gravitate in two streams rearwardly into the box or body 67 until said body or box is filled, whereupon the box or body may be dumped easily by a suitable lifting mechanism 71 connected to the front of the box. At the rear of the elevator the chains 31 pass over the sprocket wheels 40 and 41 and at the lower front pass over suitable sprocket wheels 72 and 73 and from thence along the front section 74 of the plate 28 until they pass over the sprockets 75 carried by shaft 76, which shaft is supported by depending brackets 77. Brackets 77 are formed preferably as a part of the supporting brackets 78, which supporting brackets are connected to the front section 74 of plate 28 and also to supporting uprights 79, there being any desired number of uprights 79. It will, of course, be evident that these supporting brackets may be rearranged and modified

as may be desired, without departing from the spirit of the invention.

Above the sprocket wheels 75 and toward the front of the automobile is arranged a shaft 80 carried by bracket 78, said shaft 70 accommodating the sprockets 81 so that after the chains leave the sprockets 75 they pass around the sprockets 81 and from thence around the sprockets 82 carried by shaft 83 and finally back in a diagonal direction to 75 the sprockets 40 and 41. It will be understood that the bottom 65 and the V-shaped member 70 are supported by the uprights 79 and the front section 74 of plate 28 or in any other desired manner so that when the box 80 or body 67 is dumped these members and also the elevator will remain stationary.

In order to provide a proper path or clean street for the elevator a central cleaning roller 84 is provided arranged in the front 85 of the elevator. This roller is supported by brackets 85 and 86, bracket 85 being connected directly to the plate 28 while bracket 86 is connected in any suitable manner with the frame 1, as for instance by being connected to bracket 87. The supporting shaft of brush 84 has a sprocket wheel 88 connected therewith which accommodates chain 89, and said chain passes over a sprocket 90 on shaft 91, which shaft has a beveled gear 92 meshing with beveled gear 93. Gear 93 is mounted on the sleeve 94 which is rotatably mounted on the shaft or axle 95. A clutch 96 is splined on the sleeve 94 while a gear 97 is loosely mounted on the sleeve, said 100 gear meshing continuously with gear 98 rigidly secured to the shaft 5. By this structure whenever the clutch 96 is closed power will be transmitted to the brush 84 provided the engine is operated. Brush 84 rotates in 105 proportion to the rotation of the other brushes and cleans a path in front of the elevator 27, the matter removed being discharged in the path of the brush 50.

When a small quantity of snow is to be 110 swept on an ordinary street the brush 58 is used, but where the snow is of an appreciable depth, or where other material gathered is of an appreciable depth the brushes are removed and the bevel gears 48 and 57 are also 115 removed and scrapers 99 are substituted as shown in Fig. 5. These scrapers are rigidly secured to a shaft 100 mounted in the bearing boxes 101 and 102 so as to scrape up and force the snow over toward the center 120 and eventually toward the elevator where it is elevated and discharged into the box 67.

What I claim is:

1. A street sweeping machine of the character described comprising a vehicle, an elevator formed with a horizontal bottom section and an upwardly extending section, means for pivotally connecting the rear part of the bottom section to the rear axle of the vehicle, a traveling carrier formed with a 130

- pair of chains, a plurality of sprocket wheels for guiding the chains, said sprocket wheels being positioned to cause the carrier to move over the horizontal section and then over the upwardly extending section as the vehicle moves forwardly, a plurality of runners secured to said horizontal bottom section positioned to engage the earth so as to support the forward part of the elevator, a pair of brushes carried by the vehicle overlapping the bottom section of the elevator for causing the sweepings to be engaged by said carrier, and means for moving said carrier and rotating said brushes.
- 15 2. A street sweeper comprising a vehicle, an elevator arranged on the vehicle said elevator being provided with a plate having a horizontal ground section and an upwardly extending section, a plurality of runners arranged on the horizontal section, a traveling member formed with lifting blades, means for guiding the traveling member so as to pass horizontally over the horizontal

section and then upwardly along the upwardly extending section, means for pivotally mounting the rear end of the elevator on said vehicle so that the front part will be supported by said runners and allow an up and down movement to compensate for the unevenness of the roadway, a plurality of brushes for sweeping matter on to said elevator, and means for operating the elevator in connection with said brushes.

3. A sweeping machine of the character described comprising a vehicle, an elevator arranged on the vehicle having a horizontal section, means for pivotally connecting the rear end of said elevator with the vehicle so that the front end will rest on the ground, runners for supporting one end of said elevator, diagonally arranged means for directing snow and other matter being swept to said elevator, means for operating said elevator, and means for receiving the sweepings from the upper part of the elevator.

CHAS. E. BARRIE.
